UNITED STATES PATENT OFFICE.

FRED P. SMITH, OF NEW YORK, N. Y., ASSIGNOR TO THE MUNICIPAL ENGINEERING COMPANY, OF NEW YORK, N. Y., A CORPORATION OF DELAWARE.

COMBINED CREMATORY AND LATRINE.

No. 800,177.

Specification of Letters Patent.

Patented Sept. 26, 1905.

Application filed May 5, 1904. Serial No. 206,435.

To all whom it may concern:

Be it known that I, FRED P. SMITH, a citizen of the United States, and a resident of the city, county, and State of New York, have invented a new and useful Improvement in a Combined Crematory and Latrine, of which the following is a full description.

The object of my invention is to produce a combined crematory and latrine capable of being taken apart and removed from place to place, which is at all times kept cool and free from smell or bad odors, and which may be erected and used at any convenient point without nuisance to the surroundings.

15 The accompanying drawings illustrate the invention, of which—

Figure 1 is a plan view of the interior of the crematory and latrine; Fig. 2, a vertical sectional view of the same on line 2 2, Fig. 1; 20 Fig. 3, a section on line 3 3, Fig. 2; Fig. 4, a section taken on line 4 4, Fig. 2; Fig. 5, a vertical section on line 5 5, Fig. 3; Fig. 6, a front elevation of the device.

Located within a furnace are shown in the drawings a series of hollow rotatable grate-bars forming a grate 1, which are so placed as to receive garbage or other refuse material through the dump-holes 2. Below this grate is seated another one, 3, composed, like 25 the one above, of hollow rotatable bars. The space between the grates is open, and from this space there is an outlet to a chimney 5, furnished with an adjustable damper 4. The material burned or ignited upon the upper 30 grate 1 is when in proper condition dropped upon the lower grate 3, and when sufficiently consumed is dropped into the ash-pit 6. When fires are ignited upon both grates and the damper 4 is open, there is a downdraft through 35 the upper grate and an updraft through the lower grate. Surrounding these grates is a hollow metallic frame or shell 7, and in the space between the walls of this frame the air from without circulates freely, entering there- 40 in through the openings 8. The hollow grate-bars are also journaled in the inner walls of this shell, and the air passing through the bars is warmed in its passage and, together with the air entering from without, enters 45 the space between the walls of the outer shell and escapes into the crematory through the perforations 9 in the inner wall of the frame.

50 Projecting from the furnace is a latrine 10, which extends to a distance suitable to be fur-

nished with the closets 11. Below these closets 55 is a separating-plate 12, which divides the latrine into an upper and a lower chamber 13 and 14. The solid matter from the closets falling upon the plate 12 remains there until desiccated or swept off, and the liquid passes 60 through the apertures 15 and falls upon the floor of the lower chamber 14. This lower chamber is also divided in two by the upright partition-wall 16, Fig. 4, which extends nearly to the end of the latrine, leaving a space 17 65 at its rear end. Between the latrine and the furnace is interposed a chamber 18. It is provided with dump-holes 19, and within this chamber at a level below the floor 12 of the latrine is located a pan 20. Upon this pan 70 may be dumped garbage or other refuse material, and the solid desiccated matter from the floor 12 may be swept upon it. Below the pan 20 and at the bottom of chamber 18 is another pan 21, which may be called an “evaporating-pan.” Its office is to receive the liquid matter dripping from the pan 20 and also from the floor of chamber 14 and evaporate it. This lower space between the floors is provided with doors 22. The partition-wall 80 16 divides the lower chamber 14 in two, and in one of the chambers thus formed the adjustable damper 23 is placed, and when this damper is closed and the damper 4 is open the draft to the chimney is direct from the 85 furnace through damper 4 and draws off the foul odors from the latrine, which pass over the floor 12, through chamber 18, and over the fire on grate 3. When the damper 23 is open and 4 is closed, the heat and products of 90 combustion pass from the grates through chamber 18, above floor 12, through opening 17, into chamber 14, over pan 21, into ash-pit 6, and thence through lower passage to the chimney.

95 On the front elevation of the device, Fig. 6, are shown the usual furnace-doors 24 25 26, which may be opened or closed, as required. Air admitted through the upper and lower of these doors will maintain the updraft through 100 the grate 3 and the downdraft through grate 1 when the damper 4 is open.

The whole device is constructed in sections and jointed, so as to be taken apart, removed, and reassembled. These joints are shown in 105 the drawings—in Fig. 2 at A B C D E, in the chamber between the furnace and the latrine at H and I, and in the latrine at K, L, M,

and N. The front of the apparatus is also shown in detachable sections and plates at O P Q R S T, and the sections are so made as to fit over the ends of the grate-bars and form 5 a bearing in which they can be rotated when required, leaving them so exposed that the outer air may pass through them and enter the hollow space between the walls of the frame.

10 The entire device is capable of consuming garbage or other refuse matter while carefully providing for and evaporating the drainage, and combined with a latrine whose parts coöperate with the crematory which takes off 15 and consumes all odors, consumes the solids, and evaporates the liquid therein, and the whole apparatus is constructed to be taken apart in sections moved from place to place as required, and reassembled when thus re- 20 moved.

What I claim, and desire to secure by Letters Patent, is—

1. In a combined crematory and latrine, a furnace, and a latrine having a separating- 25 chamber located between them and communicating with both, the latrine provided with

a floor for the solid and liquid matter and openings in the floor to allow the liquid matter to escape in combination with adjustable dampers and means for opening and closing 30 them to draw the odors and vapors over or under the floor of the latrine as desired.

2. In a combined crematory and latrine, a furnace composed of two or more grates composed of hollow rotatable bars and means for producing an upward or downward draft to a chimney, in combination with a latrine having an upper and lower compartments, dampers and means for adjusting the same to draw off the air from the upper compartment and 40 induce a circulation of heat through the lower compartment in its passage to the chimney, and constructed in removable sections, to permit the device to be taken apart, removed and its parts reassembled after removal. 45

In testimony whereof I have signed my name to this specification in the presence of two subscribing witnesses.

FRED P. SMITH.
